SHOWER HEAD

Ralph E. Bletcher and Clarence H. Bentley, Los Angeles, Calif., assignors of ten per cent to Ralph E. Bletcher, twelve and one-half per cent to Ernest H. Bucknell, twelve and one-half per cent to Mabel Bucknell, ten per cent to Pearl White Bletcher, twenty-five per cent to Marcia Bucknell Liston, ten per cent to James H. Bletcher, ten per cent to Hazel Bletcher Skinner, and ten per cent to Charlotte R. B. Robertson

Application February 20, 1950, Serial No. 145,284

8 Claims. (Cl. 299—130)

1

This invention relates to a new and useful shower head.

The principal object of this invention is to convert a stream of relatively high velocity water into a spray of finely divided and relatively low velocity water suitable for use in a shower bath or the like.

It frequently occurs in devices for accomplishing this result that a hollow cone of finely divided and relatively low velocity water is produced. It is an object of this invention to eliminate this hollow cone and produce a spray of relatively constant density throughout.

It is a further object of this invention to provide means for adjusting the quality or fineness of the spray.

It is a still further object of this invention to produce a spray consisting of a plurality of droplets of water as distinguished from a series of fine streams or needles of water in one position and to produce a cone of streams or needles of water in a second position.

It is a further object of this invention to provide means for flushing out the shower head without necessitating removal or dismantling of the shower head.

The preferred embodiment of our invention contemplates a housing provided with a restricted throat and a skirt, extending from the throat, dispersing means disposed in the restricted throat which slightly alters the angle of flow through said throat and disperses the water passing through said throat, means for longitudinally adjusting said dispersing means to control the dispersion of water passing through the throat, and a plurality of alternating depressed frustoconical surfaces and raised interrupted frustoconical surfaces in the skirt to assist in controlling the character of the discharge spray. It is to be understood that various changes in the size, shape and locality of the various elements can be made without departing from the scope of the invention and the accompanying claims.

Further objects and advantages of this invention will become apparent from the following description and the accompanying drawings.

In the drawings:

Fig. 1 illustrates a side elevation of a shower head attached to a water supply pipe;

Fig. 2 is a sectional view of a shower head embodying this invention with the water dispersing means at its uppermost position;

Fig. 3 is a sectional view of the shower head with the dispersing means at the flushing position;

2

Fig. 4 is a sectional view taken along the line 4—4 of Fig. 2;

Fig. 5 is an exploded view of the dispersing means and its associated parts; and

Fig. 6 is a fragmentary prospective view illustrating the restricted throat and the skirt.

The housing 10 which forms a chamber 11 may be constructed in a single casting provided with a transverse web forming a restricted throat 12 and provided with a skirt 14. It is contemplated that various changes in the shape and details of the housing may be resorted to without altering the mode of operation of this invention. In this particular form the housing 10 is provided with external threads 16 adapting the device to be attached to a water supply pipe 18 as illustrated in Figure 1.

The water dispersing means in this embodiment may be composed of a plug member 20 provided with a flange 22 as seen in Figure 5. A sleeve 24 which is made of rubber or other resilient material slidably fits on the plug member. The lower extremity of the sleeve 24 is provided with a plurality of teeth 30 forming grooves which serve to disperse the flow of water through the throat 12 as hereinafter will be described. Also at the upper extremities of the teeth 30 an annular ridge or ledge 31 is formed on the sleeve, the function of which will subsequently be described. The teeth 30 in this embodiment are not parallel to each other but they are preferably formed on the sleeve at slightly varying angles to each other which aids in dispersing the water flowing through the throat. The circumference of the sleeve about the toothed portion is slightly larger than the circumference of the restricted throat so that the teeth are slightly distorted when the plug member is held in the restricted throat which adds to the dispersion of the flow through the throat.

A pair of cup shaped members 32 and 33, the outer diameter of which corresponds to the inner diameter of the chamber 11, are provided to retain the plug member within the housing. Each of these cup members is provided with an opening in its closed end 34 and 35 adapted to fit over the upper extremity 36 of plug member 20 and are secured to the plug member by riveting extremity 36 forming head 38. Thus, the plug member 20 is slidably retained in the housing by the cup shaped members 32 and 33. Openings 40 are provided in the upper cup 32 to permit flow of water through said cup. Similarly, openings 42 are provided in the lower cup 33 which, when the cups are mounted on the plug

member 20, may be offset from the openings 40 as is shown in Figure 3 to create turbulence in the incoming flow and assist in dispersing the solid stream of water admitted into the chamber 11.

It is desirable to be able to control the position of the water dispersing means in the mixing chamber to control the character of the spray discharged from the shower head. In this embodiment of our invention, this is accomplished by the eccentric 44 which is rotated by handle 46. The pin 48 on the eccentric fits into the opening 50 of upper cup 32 through a suitable opening 51 in the housing 10 adapted to receive the eccentric. Upon rotation of the eccentric, the cup 32, carrying with it cup 33, plug member 20 and sleeve 24, are raised or lowered with respect to the restricted throat 12. When the dispersing means is raised or lowered, the cup 32 and its associated parts are rotated a slight amount, producing a scouring action in the restricted throat, thus insuring a clean unobstructed throat through which water will pass. This slight rotation of the plug member 20 and sleeve 24 also functions to vary the angularity between the teeth 30 on the sleeve since, as seen before, the circumference of the toothed portion of the sleeve is slightly greater than the circumference of the throat. Variation in the angularity of the teeth and hence distortion in the grooves between the teeth through which the water passes will alter the degree of dispersion and character of spray discharged from the shower head.

The eccentric 44 is provided with a recess 52 adapted to retain an O ring 54 to prevent leakage from the chamber 11. A similar recess 56 in the eccentric 44 is adapted to receive the locking portions 60 of the split ring 66 as seen in Figure 2. The split ring 66 is retained in the annular recess 61 in the housing 10 and a resilient washer 62 may be utilized to retain the split ring 66 in the locking position preventing lateral movement of the eccentric 44.

After the water passes through the restricted throat 12, it passes out the discharge opening 64 in the skirt 14. Around the circumference of said discharge opening are provided a plurality of alternating depressed interrupted frusto-conical surfaces 66, and raised interrupted frusto-conical surfaces 68, as best seen in Figure 6, which aid in the formation of a filled cone of the spray being discharged from the shower head.

The operation of this shower head is as follows:

Water is admitted into chamber 11 from pipe 18 under the usual pressure as found in the ordinary household. The water then passes through openings 40 of the cup 32 and through the openings 42 of cup 33. The velocity of the water is greatly increased upon passing through these restricted openings and considerable turbulence results in the cup shaped member 33. The water then passes through the restricted throat and is dispersed by the dispersing means.

The effect of the dispersing means varies with its position. At the uppermost position of the plug member as illustrated in Figure 2, the lower extremities of the teeth 30 are substantially opposite the lower edge of restricted throat 12. In this position a plurality of fine needles of water of relatively high velocity are discharged. The streams or needles of water discharged when the dispersing element is so positioned are directed

almost parallel to each other and form a spray pattern having a relatively small angle of divergence. As the dispersing means is moved downward in relation to the restricted throat 12 the angle of divergence of the needles of water and the cross-sectional area of the needles of water will be increased.

As the eccentric 44 is rotated by handle 46, the plug member 20 carrying sleeve 24 is forced downward as described before. As the teeth 30 move downward with respect to the restricted throat 12, the degree of dispersion of the water passing between the teeth 30 is increased. This is caused by the slight distortion of the teeth which accentuates the varying angularity between the teeth 30, as described before, which in turn is caused by the circumference of the toothed portion of sleeve 24 being slightly larger than the circumference of the restricted throat 12.

At a position about midway between the uppermost position of the plug member as shown in Figure 2 and the lowermost position as illustrated in Figure 3, some of the streams or needles of water pass out through the depressed interrupted frusto-conical surfaces 66 in the skirt and others are deflected slightly inwardly by the raised interrupted frusto-conical surfaces 68, the result being a cone of relatively high velocity streams or needles of water and of substantially constant density being discharged.

As the plug member is lowered, the velocity of the discharged water reduces, the amount of turbulence in the skirt increases and the streams or needles of water discharged when the plug member is at the uppermost position tend to be broken up into droplets of water. When the plug member is lowered to the position where the upper extremities of teeth 30 are slightly below the lower edge of the restricted throat 12, a large portion of the water passing through the restricted throat strikes the annular ridge or ledge 31 and the upper extremities of teeth 30 and is deflected laterally onto the inner wall of the skirt 14. This results in a cone of water being discharged which is of relatively low velocity and finely divided into droplets of water much the same as rainfall.

When the plug member is lowered to the flush position shown in Figure 3, a large volume of water may pass through the shower head to flush out any impurities which may have been entrapped in the shower head.

We claim:

1. A shower head comprising: a housing provided with a restricted throat and a skirt extending below said throat, a plug member disposed in said throat, a resilient sleeve adapted to be mounted upon said plug member and provided with a plurality of teeth at one extremity of said sleeve so that the circumference of the sleeve about the teeth bearing portion is slightly larger than the circumference of the throat and said sleeve also provided with an annular ridge immediately above the teeth bearing portion of said sleeve; and means for longitudinally adjusting said plug member in said housing.

2. A shower head comprising: a housing provided with a restricted throat and a skirt extending below said throat, a plug member disposed in said throat, a resilient sleeve adapted to be mounted upon said plug member and provided with a plurality of teeth of varying angularity with respect to the longitudinal axis of the sleeve at one extremity of said sleeve so that the circumference of the sleeve about the teeth bearing portion is slightly larger than the circumference

of the throat and said sleeve also provided with an annular ridge immediately above the teeth bearing portion of said sleeve, and means for longitudinally adjusting said plug member in said housing.

3. A shower head comprising: a housing provided with a restricted throat and a skirt extending below said throat, a plug member disposed in said throat, a resilient sleeve adapted to be mounted upon said plug member and provided with a plurality of teeth at one extremity of said sleeve and also provided with an annular ridge immediately above the teeth bearing portion of said sleeve, means for longitudinally adjusting said plug member in said housing, and a plurality of alternating depressed interrupted frusto-conical surfaces and raised interrupted frusto-conical surfaces provided in said skirt.

4. A shower head comprising: a housing provided with a restricted throat and a skirt extending below said throat, a plug member disposed in said throat, a resilient sleeve adapted to be mounted upon said plug member and provided with a plurality of teeth at one extremity of said sleeve so that the circumference of the sleeve about the teeth bearing portion is slightly larger than the circumference of the throat and said sleeve also provided with an annular ridge immediately above the teeth bearing portion of said sleeve, means for longitudinally adjusting said plug member in said housing, and a plurality of alternating depressed interrupted frusto-conical surfaces and raised interrupted frusto-conical surfaces provided in said skirt.

5. A shower head comprising: a housing provided with a restricted throat and a skirt extending below said throat, a plug member disposed in said throat, a resilient sleeve adapted to be mounted upon said plug member and provided with a plurality of teeth at one extremity of said sleeve and also provided with an annular ridge immediately above the teeth bearing portion of said sleeve, means for slidably retaining said plug member in said housing, an eccentric which cooperates with said means to longitudinally adjust said plug member in said housing, and a locking member retained in said housing, portions of which engage and retain said eccentric in said housing.

6. A shower head comprising: a housing provided with a restricted throat and a skirt extending below said throat, a plug member disposed in said throat, a resilient sleeve adapted to be mounted upon said plug member and provided with a plurality of teeth at one extremity of said sleeve and also provided with an annular ridge immediately above the teeth bearing portion of said sleeve, means for slidably retaining

said plug member in said housing, and an eccentric which cooperates with said means to longitudinally adjust said plug member in said housing and to rotate said plug member in said throat during said longitudinal adjustment.

7. A shower head comprising: a housing provided with a restricted throat and a skirt extending below said throat, a plug member disposed in said throat, a resilient sleeve adapted to be mounted upon said plug member and provided with a plurality of teeth at one extremity of said sleeve and also provided with an annular ridge immediately above the teeth bearing portion of said sleeve, means for slidably retaining said plug member in said housing, an eccentric which cooperates with said means to longitudinally adjust said plug member in said housing and to rotate said plug member in said throat during said longitudinal adjustment, and a locking member retained in said housing, portions of which engage and retain said eccentric in said housing.

8. A shower head comprising: a housing provided with a restricted throat and a skirt extending below said throat, a plug member disposed in said throat, a sleeve mounted upon said plug member and provided with a plurality of teeth extending generally axially completely to the bottom extremity of said sleeve and also provided with a transverse ledge immediately above the toothed portion of said sleeve, the diameter of said toothed portion being of the same order of magnitude as the diameter of said throat, and means for longitudinally adjusting said plug member in said housing from an upper position wherein the toothed extremity of said sleeve is in said throat to a lower position wherein said annular ledge is below said throat whereby water flowing through said shower head is discharged in the form of jets of water when said plug is in said upper position and as a plurality of droplets when said plug is in said lower position.
